UNITED STATES PATENT OFFICE.

CATHARINE A. GRISWOLD, OF NEW YORK, N. Y.

DESIGN FOR THE ORNAMENTATION OF CORSETS.

SPECIFICATION forming part of Design No. 19,234, dated July 30, 1889.

Application filed June 29, 1889. Serial No. 316,094. Term of patent 14 years.

To all whom it may concern:

Be it known that I, CATHARINE A. GRISWOLD, of the city, county, and State of New York, a citizen of the United States, have 5 invented and produced a new and original Design for the Ornamentation of Corsets, of which the following is a full, clear, and exact description, reference being had to the accompanying drawing, forming part of this specification.

The single figure in the drawing represents in side elevation a corset containing my invention.

The leading and special feature of my new 15 design consists in a band or stripe which is curved or bent upon itself about midway its ends and the ends of which are approximately rectilinear and converge toward each other, and which band thus shaped extends from 20 the lower edge of the corset longitudinally toward the waist-line thereof.

A represents a corset, which may be in the usual and ordinary form.

B represents a band or stripe, which has 25 about midway its ends the curve or bend upon itself shown at b, and the two ends b' b² of which are each approximately rectilinear in outline and direction and converge toward each other at their free ends, as shown. The band or stripe thus shaped extends from at 30 or about the lower edge of the corset longitudinally upwardly in the direction toward the waist-line of the corset.

What I claim is—

The design for the ornamentation of a corset 35 herein described and shown, the same consisting in a band or stripe B, which has the curve or bend b upon itself about midway its ends, and the said ends b' and b² of which are approximately rectilinear in direction and converge toward each other at their free extremities, said band or stripe thus shaped extending longitudinally upwardly from the lower edge of the corset toward the waist-line thereof. 40

CATHARINE A. GRISWOLD.
